UNITED STATES PATENT OFFICE.

HORACE GREELEY MORROW, OF BERKELEY, CALIFORNIA, ASSIGNOR TO STANDARD OIL COMPANY, OF RICHMOND, CALIFORNIA, A CORPORATION

GREASE-GUN.

1,263,590.

Specification of Letters Patent. Patented Apr. 23, 1918.

Application filed February 8, 1917. Serial No. 147,432.

To all whom it may concern:

Be it known that I, HORACE GREELEY Morrow, a citizen of the United States, residing at Berkeley, in the county of Alameda and State of California, have invented certain new and useful Improvements in Grease-Guns, of which the following is a specification.

The present invention relates to a grease-
10 gun of the type having a manually operated piston operating within a barrel, and a nozzle for directing the issuing stream of grease.

Devices of this type are used principally
15 for applying lubricating oil or grease, of comparatively soft consistency, to the moving parts of various forms of machinery, and are most extensively used in the lubrication of automobiles or other motor vehicles. The object of the present invention is
20 to provide such a device which may be conveniently carried, loaded with oil or grease, in the tool-box or elsewhere in the vehicle, without danger of leakage or spilling of the contents. As such, the device constitutes an
25 emergency grease-gun, for the reason that it may be carried in the automobile, in a condition ready for instant use. The necessity for carrying an empty grease-gun, and a
30 separate container for the grease, is thus obviated. A further object of the invention is to provide a grease-gun which occupies as little space as possible when loaded, a factor which adds to its convenience.

35 In the accompanying drawings, and in the following specification, the invention is illustrated and described in its preferred form, but it is to be understood that changes, within the scope of the claims hereto appended, may be made in the form and construction without departing from the spirit of the invention. With this in view, the invention will now be fully described with reference to the accompanying drawings,
40 wherein

Figure 1 is a part sectional elevation of my improved grease-gun, showing the position of the parts when the gun is loaded.

Fig. 2 is a similar view showing the position of the parts when the gun is in operation.

Referring more particularly to the drawings, the reference numeral 1 designates a barrel, to the ends of which are secured as
55 by means of screw threads, end caps 2 and 3.

The cap 2 has extending from it a tip or nozzle 4, curved as shown, and terminating in a laterally directed discharge aperture 5. The opposite cap 3 is formed with a central
60 guide aperture 6.

Within the barrel is a piston, formed in any well known manner, as, for example, by a pair of oppositely disposed cup leathers 7, a back plate 8 between said leathers, and a pair of front plates 9, one within the cup
65 of each leather, the whole being securely held between two nuts 10 screwed upon the end of the lineally disposed piston rod 11.

Said piston rod 11, which extends through the guide 6 in the head 3, is jointed at two
70 places, 12 and 13, adjacent the piston, and is thereby enabled to be folded over outside said head 3, and to lie parallel with and adjacent the side of the barrel 1, as shown in Fig. 1, when the piston is fully withdrawn
75 toward said head 3, in which position the gun is loaded, ready for use. The hinge joints 12 and 13 in said rod are formed upon one side with square corners 14, to prevent bending in the other direction at said joints,
80 so that the rod 11 will not tend to buckle inside the barrel, when pressure is applied thereto. Notches 15 and 16 are formed in
85 the edges of the respective caps 2 and 3, within which said rod 11 lies when folded over.

The rod 11 is longer than necessary to operate the piston throughout its entire stroke, and when folded over, as shown in Fig. 1, the end of said rod, which carries
90 a suitably formed handle 17, extends out beyond the end of the barrel approximately as far as the nozzle 4. A loop or yoke 18, preferably formed of spring wire, is pivotally connected with said rod 11 at 19, near
95 its end, the wire of said loop being passed through a transverse hole in said rod. A cap 20 is carried by the outer end of said loop 18, said cap being adapted to fit over
100 the end of the nozzle 4, and close the discharge aperture 5 therein. Said cap 20 is preferably formed with a groove terminating in a shoulder 21, to insure the proper positioning of the cap upon the end of the nozzle; and said cap is retained upon said
105 nozzle by the spring in the unsupported end portion of the rod 11, and also by the spring in the loop 18, whose side members are preferably slightly bowed for this purpose.

It will thus be seen that the gun may
110

be carried fully loaded and ready for emergency use, and still occupy small space, by reason of the folded position of the rod 11; and also while loaded, its discharge is covered and protected.

I claim:—

1. A grease-gun comprising a barrel having a discharge aperture at one end; a piston within said barrel; an operating rod secured to said piston and extending through the other end of said barrel, said rod adjacent the piston being jointed to enable it to lie substantially parallel with and adjacent the outside of said barrel when the piston is retracted therein; and means carried by the free extremity of said rod for closing the discharge aperture of the barrel.
2. A grease-gun comprising a barrel having a discharge aperture at one end; a piston within said barrel; an operating rod secured to said piston and extending through the other end of said barrel, said rod adjacent the piston being jointed to enable it to lie substantially parallel with and adjacent the outside of said barrel when the piston is retracted therein; and said rod having a length sufficient to carry its free extremity into proximity with the discharge aperture of the barrel, when said rod is lying beside the barrel; and a closing device for said discharge aperture, carried by the free extremity of the rod.
3. A grease-gun comprising a barrel having a discharge aperture at one end; a piston within said barrel; an operating rod se-

cured to said piston and extending through the other end of said barrel; a pair of spaced pivotal joints in said rod adjacent the piston to permit the same to be deflected out of a straight line, in one direction only, and enable it to lie substantially parallel with and adjacent to the outside of the barrel when the piston is retracted; and means carried by the free extremity of said rod for closing said discharge aperture.

4. A grease-gun comprising a barrel; heads associated with the ends of said barrel and having alined notches formed in their outer peripheries, one of said heads having a discharge aperture and the other having a piston rod guide; a discharge nozzle extending from the discharge head and terminating in a laterally directed discharge orifice; a reciprocative piston within said barrel; an operating rod secured to said piston and extending through said guide; a pair of spaced pivotal joints in said rod adjacent the piston to permit said rod when the piston is fully retracted, to lie parallel with and adjacent to the outside of the barrel and within the said notches in the heads thereof; and means carried by the free extremity of said rod for closing the discharge orifice of said nozzle.

In testimony whereof I have signed my name to this specification in the presence of two subscribing witnesses.

HORACE GREELEY MORROW.
